UNITED STATES PATENT OFFICE.

JACOB WM. DE CASTRO, OF NEW YORK, N. Y.

ELECTRIC SAFETY DEVICE FOR ELEVATORS.

SPECIFICATION forming part of Letters Patent No. 298,851, dated February 19, 1884.

Application filed November 27, 1883. (No model.)

To all whom it may concern:

Be it known that I, JACOB W. DE CASTRO, a citizen of the United States, and a resident of the city, county, and State of New York, have invented certain Improvements in Electric Safety Devices for Elevators, of which the following is a specification.

My invention is a safety device for elevators, whereby I am enabled to utilize directly the power of an electric current to arrest the movement of the cage should the supporting-ropes break, obviating the uncertain and dilatory action of ordinary mechanically-operated detents.

15 In the drawings, Figure 1 is an elevation showing a cage and sufficient of the guides and safety appliances to illustrate my invention. Fig. 2 is a sectional plan of Fig. 1. Fig. 3 is an elevation of the cage, showing a modification. Figs. 4 and 5 are side views of the safety-magnets, illustrating modifications.

The invention is applicable to all styles of cages and different arrangements of guides, but is shown in connection with an ordinary 25 sliding platform, A, and side guides, B B.

At suitable points upon the platform-frame are arranged the safety electro-magnets C, each with the end of its soft iron core e adjacent to but free from contact with an iron rail or strip, 30 a, secured to the guide. In connection with the parts thus arranged I use a battery or other generator, G, wires from which include all the magnets C in their circuit, and a circuit-breaker or key is connected in any suitable 35 manner with any part of the apparatus, so that should the cable break or the cage attain undue speed the circuit will be completed, the electro-magnets excited, and the magnetic action between the cores e and rails a will constitute such a strong break as will arrest the 40 further movement of the cage.

Different means of maintaining the electric connections during the movement of the cage may be employed. In the drawings I show 45 copper strips b, with which contact rollers c, carried by arms d, projecting from the cage-frame make contact. Wires s s' s² s³ s⁴ s⁵ constitute the connections between the battery, strips b, and magnets, and wires s⁶ s⁷ complete 50 the circuit in connection with a circuit-break-

er, O. This, as shown, consists of a pillar, g, connected to the wire s⁶, and arm u, secured to the suspension-bolt o and connected to the wire s⁷, and a spring, m, serves to throw down the bolt and bring the arm against the pillar when the cable breaks. Where it is desired to apply the brake, should the cage acquire an undue speed without the rope breaking, a wing, fan, governor, or other device may be arranged to cause the completion of the circuit. For instance, the counterbalanced fan or wing W (dotted lines, Fig. 1) will, if the speed is too great, be lifted by the action of the air, and will bring the switch u' in connection with the pillar g. A greater retarding effect may be 65 secured by making either the magnets or their cores or the rails a movable, so as to insure actual contact between the cores and the rails when the magnets are excited.

When safety-racks are substituted for rails, 70 as shown in Figs. 4 and 5, the magnet-frame may slide on a bracket, P, secured to the cage-frame, and a spring, q, may serve to hold back the magnet until it is excited, as in Fig. 4, or the spring may be connected to a sliding 75 core in a stationary magnet, as in Fig. 5.

Instead of putting the magnets in one circuit, each may be in a separate circuit, as shown in Fig. 3. Where a magneto-generator is employed, it may be run usually with but 80 little power, as the only force required so long as the circuit is broken is that needed to revolve the armature-shaft.

Without limiting myself to the precise construction and arrangement shown, I claim— 85

1. An electro safety device for elevators, consisting of iron strips upon or adjacent to the guides, electro-magnets, with the ends of their cores adjacent to said strips, a circuit-closer, and connections whereby, upon any undue increase of speed, the circuit is completed and the magnets excited, substantially as set forth.

2. The combination, with a cage supporting electro-magnets and connections, and a circuit-closer arranged to complete the circuit and excite the magnets should the cage part from its cable or attain undue speed, of iron strips arranged opposite the cores of the magnets to insure a magnetic retarding effect 100

when the magnets are excited, substantially as set forth.

3. The combination of a movable cage carrying electro-magnets, safety-detents, and a circuit-closer, a stationary generator, and strips *b* in the electric circuit, and circuit-connections on the cage, moving in contact with said strips, substantially as set forth.

4. The combination of the cage, magnets, to automatic circuit-closers, strip *a*, generator, and connections, as described, whereby to

complete the circuit in case the cage attains undue speed, and to then insure contact between the cores and strips on the magnets becoming excited, substantially as specified.

In testimony whereof I have signed my name to this specification in the presence of two subscribing witnesses.

JACOB WM. DE CASTRO.
